SLIP COVER

Theodore M. Waranch, Baltimore, Md., assignor
to The Comfy Manufacturing Company, Balti-
more, Md., a corporation of Maryland

Application August 8, 1944, Serial No. 548,542

2 Claims. (Cl. 155—182)

1

This invention relates to improvements in furniture slip covers and has for its general object the provision of a slip cover which is so constructed that it can be neatly and snugly attached to any one of several sizes of a particular type or style of upholstered chair even when made entirely of a relatively non-stretchable fabric material.

Another object of the invention is to provide a unitary slip cover which can be made economically in large quantities from non-stretchable fabrics and which is so constructed that it will readily adapt itself to any one of a number of sizes of chair of a particular type to give the snug, neat and attractive appearance characteristic of tailor-made slip covers.

A further object of the invention is to provide an improved unitary slip cover of such construction that it can be placed snugly and smoothly on an article of furniture and removed therefrom with a minimum of effort and can be laundered with convenience.

Other objects and advantages of the invention will become apparent after a perusal of the following description when read in connection with the accompanying drawings in which Fig. 1 is a front perspective view of an overstuffed chair having a slip cover thereon embodying the present improvements; Fig. 2 is a rear perspective view of the chair and cover, the cover being broken away at several places to illustrate its construction more clearly; Fig. 3 is an assembly plan view of the several sections or panels of the cover and Fig. 4 is a perspective view illustrating a detail of the cover construction.

The cover of this invention is of particular advantage for the use of non-stretchable fabrics, such as, chintz, cretonne, linen and the like, although obviously it may be made of stretchable materials or combinations of the former and the latter. As is shown in the drawings, the cover includes a seat panel A which covers the top of the chair seat beneath the cushion and is connected along its rear edge to the bottom edge of the back rest panel B, the seam connecting such edges of panels A and B extending between the points 2, 2 on panel A and extending between the points 5, 5 on panel B. The combined length of the panels A and B is greater than the combined height of the chair and the depth of the seat so that there is provided a surplus of material which may be tucked into the crevice between the back and seat cushions of the chair and which is indicated in dotted lines in Fig. 1 of the drawings. The front edge of panel A is

2

substantially equal in length to the width between the arms of the chair and extends across the front of the chair seat from the points of juncture of the inner sides of the front faces of such arms with the front of the chair seat (note Fig. 1). The sides of the seat panel A diverge rearwardly from the front edge thereof so that there is formed a portion of excess material on each side of the seat panel (Fig. 3) which provides tuck-in material to be inserted into the crevices between the seat and arm cushions, as is indicated by the dotted lines along the inner side of the chair in Fig. 1 of the drawings.

The back rest panel B along its line of juncture 15 5—5 with the rear edge of the seat panel A is substantially equal in width to the latter. From the points 5, 5 of panel B, the side edges of such panel curve outwardly to provide the diverging concavely-shaped side edge portions 5—14, 5—14 which are seamed between the points 6—14, 6—14 to the rear edge portions 7—13, 7—13 of the arm panels C, the side edge portions 5—14 of panel B between the points 5—6, 5—6 thereof being seamed to the inner side edges of panels C between the points 3—7, 3—7 thereof. The major portions of seams joining the edge portions 6—14 of panel B with the edge portions 7—13 of arm panels C are designed to be tucked into the crevices of the chair between the back rest cushion and the arm cushions, the configuration of panels B and C along such seams providing surplus material for this purpose. The edges of panels B and C forming said seams are of such length that at their upper or outer ends they are adapted to extend around the sides of the back rest panel to the rear of the chair, as is clearly shown in Fig. 2 of the drawings. This is also shown in Fig. 4 of the drawings, which more clearly illustrates the manner in which the edge portions 6—14 and 7—13 of panels B and C, respectively, are seamed together and the manner in which the cover naturally assumes the configuration of the chair due to the peculiar forms of such edge portions. From the points 14, 14 30 40 45 of panel B, the sides of such panel curve upwardly toward each other in a convex manner to form a top edge portion which has a curved though somewhat flattened form. The end portions of the convexly-shaped edge of panel B, between the points 14 and the points 15 thereof, are free and unattached and are finished in any suitable manner. The central portion of such convexly-shaped edge, between the points 15, 15 50 55 is connected to the top edge of the rear panel E, the line of juncture of panel E with panel B

extending between the points 16, 16. It will be noted in Fig. 3 of the drawings, that the edge portion 15-15 of panel B is substantially greater than the edge portion 16-16 of panel E. In the cover the edge portion 15-15 is shortened to the same length as edge portion 16-16 by providing tucks F (see Fig. 2) in edge 15-15 adjacent to the ends thereof. The tucks F not only provide a snug fit of panel B around the upper curved ends of the chair but also bring the edge portions 14-15, 14-15 thereof into a somewhat vertical position when the cover is on the chair (see Fig. 2). As is also shown in Fig. 2, the transverse width of panel B in the region of the edge portions 14-15 thereof, is such, that the edge portions 14-15 of such panel are adapted to be drawn around to the rear of the chair. The edge portion 15-15 of panel B is joined to the edge portion 16-16 of panel E by a binding or welting G which is adapted to extend across the top of the chair so that when the cover is in position on the chair, the edge portion 15-15 forms the top edge of panel B, while from the points 15 to the points 14 thereof, the edge portions of panel B are drawn to the rear of the chair and form generally a part of the side edges of the cover, as is shown more clearly in Fig. 2 of the drawings.

Connected to the seat panel A and back rest panel B are two arm compartments, each being composed of a panel C adapted to cover the inner and outer side surfaces of an arm of the chair and a front panel D adapted to cover the front face of such arm. As will be more readily understood from Fig. 3, the inner side edges of panels C from the points 4 to the points 3 thereof, are connected to the side edges of seat panel A defined by the points 1-2. As has been mentioned, the inner side edges of panels C, from the points 3 to the points 7 thereof are connected to the back rest panel B from the points 5 to the points 6 of the latter. The rear edges of such panels C from the points 7 to the points 13 thereof are seamed to the edge portions 6-14, 6-14 of panel B as has been described, so that the rear edges designated 12 of panels C form a continuation of the edge portions 15-14 of panel B and are suitably finished in a like manner. The dimensions of panels C are such that they cover the inner, top and exterior surfaces of the arms while providing with panels A and B excess material to be tucked into the crevices between the arm, seat and back rest cushions of the chair and providing sufficient length on the outer covering portions thereof to enable the rear edges 12 of such panels C to be drawn with the edge portions 14-15 of panel B, around to the back of the chair, as is illustrated in Figs. 2 and 4 of the drawings.

The front edges of the arm panels C are connected to the side and top edges of the front face panels D, D in such manner that the inner ends of such front edges, i. e. points 4 thereof, are connected to the lower ends of the inner sides of panels D, designated 9 in Fig. 3, and at points short of the juncture of such front edges with the outer side edges 11 of panels C, i. e. points 8 thereof, are joined to the lower ends of the outer sides of panels D which are designated 10 in Fig. 3 of the drawings. The front edge portions 4-8 of panels C are joined to the substantially U-shaped edge portions 9-10 of panels D by strips of binding or welting H which define the front face panels. From the points 8 to the outer side edges 11 of panels C, the front edges of such panels are free and unconnected, and are finished in any

suitable manner. The outer side edges 11 of panels C, C are also unconnected to any of the other panels and are adapted to hang along the outer sides of the arms along a line below the lower ends of the front face panels D as is shown in Figs. 1 and 2 of the drawings.

Rear panel E except for its connection along its edge portion 16-16 with panel B is unconnected to the other panels of the cover. The binding or welting G continues from such juncture with panel B to the bottom edge of panel E to give the side edges 17, 17 of the latter a finished appearance. The length of panel E is such that the free bottom edge thereof which is finished in any suitable manner, extends along a line below the lower ends of the front face panels D and slightly above the edges 11 of panels C when the cover is on the chair, as is shown in Figs. 1 and 2 of the drawings.

Connected to the slip cover is a skirt composed of an upper elongated plain panel I and a lower pleated strip J which depends from the plain panel I. The top edge of the plain panel I is provided with a binding or welting K. The skirt is connected intermediate its ends to the panels A and D, such connected portion of the skirt being indicated in Fig. 3 by the points 19, 19 and being joined to the bottom edges of the panels D and the front edge of panel A which are in substantial alignment. The skirt from the points 19 to the ends thereof are free and unconnected to the body of the slip cover. The panel I and pleated strip J of the skirt have a length greater than the combined lengths of the four sides of the chair so that the free ends thereof may be connected in overlapping relation at the rear of the chair, as is shown more clearly in Fig. 2 of the drawings. The combined width of panel I and strip J of the skirt is such that the skirt covers the lower part of the chair from approximately the top of the permanent seat cushion to a point several inches above the floor (note Fig. 1).

From the foregoing, it is believed that it will be evident that this slip cover can be easily and perfectly applied to a chair and that when in position thereon will give the snug, neat appearance that is characteristic of tailor-made covers. One way in which the cover may be applied to the chair is to first insert the pocket formed by the upper ends of panels B and E over the top edge of the back of the chair and while maintaining the upper central portion of the welting G in proper position along such top edge, smooth the back rest panel against the back cushion of the chair. The arm compartments are then placed in proper position over the arms of the chair. With the arm compartments properly positioned, the outer covering portions of panels C are drawn snugly into position against the exterior surfaces of the chair arms and may be secured in such position by means of fastening hooks 20 provided on the front edges of panels C between the points 8 and outer bottom or lower edges 11 thereof, and fastening hooks 21 provided at the lower ends of the rear edges 12. When the hooks 20 are employed, they are secured to the upholstery of the chair so that the front edge portions of panels C between points 8 and bottom edges 11 are in substantial alignment with the front corners of the chair below the seat, while when the hooks 21 are employed, they are secured to the upholstery at the rear of the chair after the rear portions or extensions of the outer covering portions of panels C have been drawn around to the back of the chair. With the outer cover-

ing portions of panels C thus fixed, the edge portions 14—15, 14—15 of panel B and edges 12 of panels C are secured in proper position at the rear of the chair by means of fastening hooks 22 provided along the side edges 17 of the rear panel E, note Fig. 2. The next step may be to tuck the excess materials of panels A, B and C into the crevices between the arm, back and seat cushions so that such panels snugly cover the surfaces of such cushions. With the body of the cover mounted on the chair the two free ends of the skirt are drawn over the outer portions of panels C and panel E and are secured in overlapping relation by the fastening hooks 23 provided on the free ends of such skirt.

It will also be understood from the foregoing, that the cover of this invention, while made in a standardized size for any particular style of chair, can be snugly and neatly fitted on all chairs of that type but having different dimensions which may vary over a considerable range. This accomplishment is due to the surplus material which is provided along the joined edges of panels A, B and C for tucking into the crevices formed by the cushions between the arms, back and seat of the chair, to the novel arrangement of the panels B and C with relation to the rear panel E, which enables the rear ends of the arm panels C and the upper side edge portions of the back rest panel B to be drawn around to the back of the chair and thereby take up any surplus material of such panels and position them snugly on the chair cushions they overlie, to the unconnected relation of the outer lower edges of the panels C with the rear panels E and the skirt which enables a snug fit over the outer side surfaces of the arms without the formation of any wrinkles due to uneven stresses on such portions of panels C, and to the peculiar connection of the skirt with the body of the cover. In this connection, the method of securing the lower edge portion of panel B, between the points 5 and 6 thereof, to the inside lower edges of panels C to provide tuck in material, also prevents pull from being exerted on the panels in this region by the material tucked in. With regard to the rear ends of the arm panels C and the upper side edge portions of the back rest panel B, the cover is preferably so designed, that for one size of chair in a particular style, there will be a six inch overlap at the back of the chair. This will provide sufficient material for larger dimensioned chairs of that style and the dimensions are so chosen that for the smallest chair of that style, the overlap at the rear will be from eight to ten inches. The method of connecting the skirt to the cover panels also increases the flexibility of fitting of the cover and enables it to be adjusted properly and snugly on the particular chair being covered. For example, the skirt permits with equal facility the proper fitting of the cover whether the chair slopes to the rear or whether it is horizontal from front to rear and without the formation of untidy bulges or folds in panels C and E to give a good appearance. The skirt disclosed is also of equal importance in fixing the positions of the several parts of the cover with relation to the chair. Thus the counterpull exerted on the panels connected to the skirt, due to the pull exerted on both ends of the skirt, holds the lines of the cover to conform to the lines of the chair covered. This counterpull also prevents shifting and sagging of the cover, eliminates the necessity for repeatedly tucking in and readjusting the cover after each use and holds the outer covering por-

tions of panels C in position without strain or pull thereon, thereby preventing the formation of folds or creases which would result from such strains, and also enables the arm panels to be shifted slightly without causing the skirt to be pulled up, the skirt holding the arm panel resiliently so that it is enabled to return to its proper position after being misplaced by normal usage. It will also be noted that the cover by reason of its peculiar, open construction, can be applied to the chair with ease and can be secured with facility by any one of a number of methods. In this connection it might be pointed out that the means for fastening the back rest and rear panels in position also prevent any tendency of these panels to shift during use. When in position on the chair, the cover's construction is such that it gives an unusually smart appearance, different from that of the usual ready made cover and more like the custom-made cover, as will be readily apparent from Figs. 1 and 2 of the drawings. The cover can be removed readily from the chair by simply unhooking the fastening members and drawing it off and without the necessity of careful manipulation to avoid strain on or rupturing of seams, as is the necessary practice with ordinary slip covers. This construction also enables the several panels of the cover to be spread out in a relatively flat condition so that all surfaces thereof can be ironed readily, thereby enabling the housewife to keep the cover in a neatly laundered condition without much trouble. This relatively flat form of the cover when not in use also facilitates its packing and storage in relatively small places.

While I have described and shown a preferred form of my invention, it will be understood by those in the art, that various changes and modifications may be made without departing from the spirit of the invention or the scope of the appended claims.

I claim:

1. A slip cover having a body portion comprising covering panels for the back rest, rear, seat and arms of a chair, said rear panel being connected along its top edge to said back rest panel and having side edges unconnected to said back rest and arm panels, the upper part of said back rest panel, intermediate said arm panels and its connection with said rear panel, having such dimensions as to provide side edge portions adapted to be drawn around to the rear of the chair into underlapping relation with the unconnected side edges of said rear panel, said arm panels each having an inner edge secured to a side edge of said seat panel, a front edge connected from its inner end to a point short of its outer end to the side and top edges of a front face panel, and an outer edge and a rear edge unconnected and free from the body of the cover, a front face panel associated with each arm panel to form an arm compartment and having its side and top edges connected as aforesaid to the front edge of an arm panel, and its lower edge in substantial alignment with the front edge of said seat panel, the portion of the front edge of said arm panel that is unconnected to said front face panel extending from the latter's lower edge to the outer edge of such arm panel, whereby the outer end portions of the arm panels are unconnected and free from the body of the cover, the outer end portions of said arm panels having such length as to enable the free rear edges thereof to be drawn to the rear of the chair, fastening means provided on the side edges

of said rear panel and adapted to secure the latter in overlapping relation on the portions of said arm and back rest panels that are drawn to the rear of the chair, and a skirt connected intermediate its ends to the front edge of said seat panel and the aligned lower edges of said front face panels and having two free ends of such length as to overlie the unconnected outer end portions of the arm panels and said rear panel and to come into overlapping relation at the rear of the chair, and means for adjustably connecting the overlapping ends of said skirt together.

2. A slip cover having a body composed of covering portions for the back rest, rear, seat and arms of a chair, said rear portion being connected along its top edge to said back rest portion and having side edges unconnected to said back rest and arm covering portions, the upper part of said back rest portion having such dimensions as to enable its side edges, intermediate said arm portions and its connection with said rear portion, to be drawn around to the rear of the chair into underlapping relation with the unconnected side edges of said rear portion, said arm portions being adapted to cover the inner and outer faces of the arms of a chair and each having an inner edge secured to a side edge of said seat portion, a front edge connected from its inner end to a point short of its outer end to the side and top edges of a front face panel, and an outer edge and a rear edge unconnected and free from the body of the cover, a front face panel associated with each arm portion to form an arm compartment and having its side and top edges connected as aforesaid to the front edge of an arm portion, the part of the front edge of said arm portion that is unconnected to said front face panel extending from point in substantial alignment with the front edges of said seat portion to the outer edge of said arm portion, whereby the outer, lower end parts of such arm portions are un-

10

15

20

25

40

connected and free from the body of the cover and depend freely over the outer, lower faces of the sides of a chair, the outer ends of said arm portions having such lengths as to enable the free rear edges thereof to be drawn to the rear of the chair, fastening means provided on the side edges of said rear portion and adapted to secure the latter in overlapping relation on the edges of said arm and back rest portions that are drawn to the rear of a chair, and a skirt connected intermediate its ends to the front edge of said seat panel and having two free ends of such lengths as to overlie the unconnected outer end parts of the arm portions and said rear portion and to come into overlapping relation at the rear of the chair, and means for adjustably connecting the overlapping ends of said skirt together.
